United States Patent Office

Des. 217,753
Patented June 2, 1970

217,753

GARMENT HANGER

John H. Batts, Grand Rapids, Mich., assignor to John Thomas Batts Inc., Zeeland, Mich., a corporation of Michigan

Filed Jan. 21, 1969, Ser. No. 15,427

Term of patent 14 years
The portion of the term of the patent subsequent to
Mar. 5, 1982, has been disclaimed

Int. Cl. D6—07

U.S. Cl. D80—8

FIG. 1.

FIG. 4.

FIG. 5

FIG. 3.

FIG. 2.

FIG. 6.

FIG. 1 is a perspective view of a garment hanger showing my new design;

FIG. 2 is a side elevation thereof;

FIG. 3 is a rear elevation thereof;

FIG. 4 is a top plan view thereof;

FIG. 5 is a bottom plan view thereof; and

FIG. 6 is a cross-sectional view taken along plane VI-VI of FIG. 3.

I claim:

The ornamental design for a garment hanger, substantially as shown and described.
